UNITED STATES PATENT OFFICE.

BENNETT BERENSTEIN, OF NEW YORK, N. Y.

SHIRT.

SPECIFICATION forming part of Letters Patent No. 584,979, dated June 22, 1897.

Application filed January 21, 1897. Serial No. 620,082. (No model.)

To all whom it may concern:

Be it known that I, BENNETT BERENSTEIN, of the city, county, and State of New York, have invented a new and Improved Shirt, of which the following is a full, clear, and exact description.

The object of the invention is to provide a new and improved shirt constructed to insure durability and strength, especially in the sleeve portions, and to form a lining to render the shirt very comfortable and warm.

The invention consists of certain parts and details and combinations of the same, as will be fully described hereinafter and then pointed out in the claim.

Reference is to be had to the accompanying drawings, forming a part of this specification, in which similar characters of reference indicate corresponding parts in all the figures.

Figure 1 is a front view of the improvement with parts broken out. Fig. 2 is a transverse section of the same on the line 2 2 of Fig. 1. Fig. 3 is a face view of the blank for forming the body of the shirt; and Fig. 4 is a similar view of the blank for forming the sleeves, shoulder, back, and front or bosom of the shirt.

The improved shirt is provided with a body A, made from a single piece of fabric, as shown in Fig. 3, the said shirt being provided with a second part B, likewise made from a single piece of fabric, as shown in Fig. 4, and combining the sleeves B' B², the shoulders B³, the front or bosom B⁴, and a portion of the back B⁵.

The body A has its middle portion A' fitted on the inside of the bosom B⁴, the shoulders B³, and the back B⁵, so as to form a lining for the same, the lower edges of the bosom B⁴ and the back B⁵ being secured by stitches C to the body A to attach the parts together. The dependent parts A² and A³ of the body A form the usual lower portion of the shirt-body, as plainly indicated in the drawings. The sides of the lining part A' of the body are connected by rows of stitches D D' to the part B at or near the junction of the sleeves B' B² with the shoulder B³. The collar E is secured in the usual manner with its neckband to the shoulder parts B³ and a corresponding portion 50 of the lining A'.

Now it is evident that by the arrangement described the body A forms a lining for the breast B⁴, the shoulder parts B³, and the back

B⁵, so that a continuous piece of fabric is on the inside of the shirt at the parts enumerated, 55 and a continuous piece of fabric extends across the shirt from the end of one sleeve to the end of the other.

By the arrangement described the continuous fabric for the sleeve and shoulder parts 60 renders seams at the junction of the same unnecessary, and as the most strain on the shirt is at this point it is evident that the shirt as constructed and above described is rendered very strong and durable and is not liable to 65 break at the junction of the sleeve and shoulder parts.

If desired, the part B may be made in two equal portions, the division being at a line B⁶, as indicated in Fig. 4, the two parts being 70 sewed together at this point in the usual manner.

It will be seen that the improved shirt has a double bosom, since the transverse piece B extends across the upper part of the longitudinal or vertical body A. It will be particularly observed that the lower edge of said transverse piece is in line with and partly below the junction of the sleeve with the body. The seam C therefore takes most of the strain 75 and very little strain comes on the seams D D'. The upper portion A' of the body is fully covered by the middle or bosom portion B⁴ of the transverse piece, as both the body and the transverse piece extend up to the neck. 80 85

Having thus fully described my invention, I claim as new and desire to secure by Letters Patent—

A shirt, comprising a body having a neck-opening and armholes, and a combined bosom; 90 reinforce, and sleeve-piece arranged upon the outer surface of the body with its ends projecting beyond the armholes thereof and forming sleeves, the central portion of the said piece extending over the shoulder of the body 95 and down the back and front of the same and secured thereto adjacent to the armholes and at its lower front and rear edges, said central portion forming a bosom and reinforce for the back and shoulders of the shirt, substantially 100 as herein shown and described.

BENNETT BERENSTEIN.
